UNITED STATES PATENT OFFICE.

JULIUS J. FERRETTI, OF NEW YORK, N. Y. ASSIGNOR, BY MESNE ASSIGNMENTS, TO THE UNIVERSAL MATCH CORPORATION, OF ST. LOUIS, MISSOURI, A CORPORATION OF MISSOURI.

PAPER-MATCH-MAKING MACHINE.

Application filed July 2, 1924. Serial No. 723,691.

This invention relates to machines for making paper matches of the type ordinarily used for advertising purposes and which consists of a plurality of pasteboard match strips joined together at one end in leaves which are usually bound together to form small books adapted to be carried in the vest pocket.

The present invention contemplates machinery for automatically producing the leaves of attached match strips ready to be bound in the usual book covers. It is the object of this invention, consequently, to provide simplified and improved mechanism for producing such leaves for match books from a roll of suitable paper or pasteboard, said machinery being capable of automatically cutting said roll at intervals longitudinally to form the laterally arranged match strips, and transversely to separate the book leaves from one another. The invention also contemplates the provision of mechanism for continually acting upon the leaves cut so as to successively dip the free ends of the match strips in paraffine, dry them, dip the tips of said match strips in an ignition substance, and discharge the completed leaves from the machine. The binding of said leaves into books may be subsequently accomplished in any suitable manner.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is a longitudinal vertical section of the front and rear end portions of a match making machine constructed substantially in accordance with this invention, intermediate parts of said machine being broken away.

Figure 2 is a broken plan view of the front portion of the machine as shown in Figure 1.

Figure 3 is a side elevation of the front end of the machine showing more particularly the driving pulley and its associated gears for operating the cutting, shaping and feeding rollers.

Figure 4 is a detailed sectional view of a portion of one of the shearing or longitudinally cutting rolls showing more clearly one

of the spring pressed punches for forming the perforations to receive the binding wires in the leaves of the match book.

Figure 5 is a detailed perspective view of one of the transverse swinging members having pins for engaging said binding perforations in order to carry said leaves through the paraffine and ignition substance applying apparatus.

Figure 6 is a longitudinal vertical section through the paraffin applying portion of the machine.

Figure 7 is a plan view of the same.

Figure 8 is a longitudinal vertical section of the portion of the machine for applying the ignition substance to the tips of the match strips.

Figure 9 is a plan view of the latter with the conveyor for the match leaves omitted for the sake of clearness.

Figure 10 is a detailed view of one of the completed leaves for a paper match book such as the present machine is capable of producing.

Figure 11 is a diagrammatic plan view of a portion of a strip of paper or pasteboard indicated in broken lines the manner in which it is cut by the machine and subsequently to separate the prepared match book leaves into narrower section if desired, and

Figure 12 is a perspective view of a match book of the kind in which the match leaves made by the present machine are bound.

The match making machine, as illustrated in the accompanying drawings, is designed to have a strip of paper or pasteboard indicated by the broken line 1 in Figure 1 fed in at the left hand end of said machine, as illustrated in said figure, and said strip of paper 1 is fed continuously through the various devices which operate thereon until discharged at the right hand end of the apparatus illustrated in Figures 8 and 9, it being understood that the portion of the machine shown in Figures 6 and 7 is arranged between that shown in Figures 1 and 2 and that illustrated in Figures 8 and 9, and that in operation the match leaves are fed automatically and continuously from one section of the machine to another until discharged in completed condition.

At the extreme left hand end of the machine a pair of superimposed shearing cylinders 2 and 3 are suitably journaled in a

- frame 4. The lower shearing cylinder 3 has a series of parallel annular grooves 5 formed therein, while the upper shearing cylinder 20 has a plurality of sets of interrupted annular cutting blades 6 formed thereon and adapted to work in the grooves 5 in the cylinder 3 for cutting or shearing the paper strip 1 longitudinally at intervals for forming the individual matches or 10 match blanks 7. As herein shown, the cylinder 2 has three sets of shearing or cutting knives 6 formed thereon with spaces 8 extending longitudinally on the surface of the cylinder between said sets of knives. 15 These spaces 8 on the cylinder tube leave transverse portions on the paper strip 1 uncut after passing between the cylinders 2 and 3, and these uncut transverse portions 9 constitute the binding portions or ends of 20 the match book leaves.
- Projecting from each of the spaces 8 between the sets of cutting knives 6 on the cylinder 2 there are two or more spring pressed punches 10, best shown in Figure 4. 25 These punches are designed to perforate the uncut transverse portions 9 of the paper strip 1, said transverse portions 9 constituting the individual match book leaves, thus forming holes therein, which may be utilized for the passage of the binding wires 11, Figure 12, which serve to hold the match leaves in the books.

After passing between the cylinders 2 and 3, the paper strip 1 passes between another 30 pair of superimposed cylinders 12 and 13 also suitably journaled on the frame 4. The upper one of these cylinders 12 carries longitudinally arranged knives 14 adapted to cooperate with the surface of the lower cylinder 13 for cutting the paper strip 1 transversely at suitable intervals according to the length of match leaf it is desired to make.

From the cylinders 12 and 13, the paper strip 1 passes between a pair of superimposed shaping cylinders 15 and 16 each having radial pins 17 spaced to engage alternate ones of the individual notches 7 of the book leaves for separating them or pressing them alternately up and down, as shown in 40 Figure 1. This shaping of the individual notches or match blanks 7 is for the purpose of separating their free ends so that they may be properly coated with paraffine and dipped in ignition material during later operations of the machine.

The pairs of cylinders 2 and 3, 12 and 13, and 15 and 16, are suitably driven by gearing from a pulley 18, Figures 2 and 3, which may be driven by a belt 19 from any suitable 50 source of power. The other operating portions of the machine may be driven by pulleys and belts or sprocket wheels and sprocket chains from the same or any other source of power as may be preferred. In 55 Figures 6 and 7, the apparatus for coating

the match blanks with paraffine is shown driven by a sprocket chain 20 engaging over a sprocket wheel 21 on a shaft 22 at the left hand end of this part of the machine, while the apparatus for applying the ignition material to the tips of the match blanks is driven by a sprocket chain 23 extending from a sprocket 24 on a shaft 25 at the right hand end of the paraffine applying section of the machine illustrated in Figures 6 and 7, to a sprocket 26 on a shaft 27 at the left hand end of the ignition material applying apparatus shown in Figures 8 and 9.

After the paper strip 1 has been cut longitudinally to form the individual match blanks, and transversely to form the book leaves, and said match blanks have been spaced apart as shown in Figure 1 by the shaping rollers 15 and 16, said leaves are fed over a belt 28 and delivered to an end- 85 less carrier 29 which conveys said leaves through the remaining operating parts of the machine. Said belt 28 may be driven from the pulley 18 by any suitable form of gearing. The conveyor 29 comprises 90 sprocket wheels 30 and sprocket chains 31 mounted thereon. While both sprocket wheels 30 are shown in Figure 1, it will be understood that the right hand one is located at the extreme right hand end of the 95 machine and that the breaks in the sprocket chains 31 and the supporting frame for the sprocket wheels are to indicate that the paraffine coating and ignition material applying parts of the machine, which are 100 separably illustrated in Figures 6 and 7, and 8 and 9, respectively, are interposed between said sprocket wheels 30 as shown in Figure 1.

The sprocket chains 31 of the conveyor 29 105 carry at equally spaced intervals swinging transverse strips or members 32 being pivotally supported by trunnions 33 projecting centrally from their ends and loosely engaging in suitable bearing 34 formed in certain 110 of the links of the chains 31. These swinging members 32 have projecting pins 35 adapted to frictionally engage the binding perforations formed by the spring punches 10 on the cylinder 2, whereby the book leaves 115 consisting of an uncut transverse portion 9 of the paper strip and a transverse series of match blanks 7 attached thereto, may be supported and conveyed by the sprocket chains 31 through the paraffin applying and ignition material tipping apparatus of the machine. The pins 35 on the swinging members 32 are engaged with the binding perforations formed in the uncut transverse portions 9 of the book leaves by means of collars 36 adapted to rotate freely with a transverse shaft 37 supported above the sprocket wheel 30 at the left-hand end of the carrier 29, said collar 36 being spaced just far enough above the swinging members 32 as they pass below 120

the same to permit the uncut transverse portions 9 of said book leaves to pass below them and have their binding perforations frictionally engaged with the pins 35. After passing from below the collars 36 the book leaves swing to the vertical position indicated with the shaped or spread apart match blanks 7 depending from the upper bight of the sprocket chains 31, in which position they 10 are conveyed through the remaining parts of the machine.

Referring to Figures 6 and 7 of the drawings; 38 indicates a tank for holding liquid paraffine, and 39 is an endless carrier mounted on an incline and having a series of buckets or transverse troughs 40 adapted to dip into the paraffine and raise sufficient thereof to coat the match blanks of each book leaf as it passes over said tank 38. It will be understood, of course, that the timing of the movement of the buckets 40 and the passage of the book leaves depending from the carrier 29 over the tank 38 is such as to insure the registering of a bucket full of paraffine as it is raised from the tank with the depending and spaced apart match blanks of each book leaf. The left hand end of the carrier for the buckets 40 is arranged somewhat higher than the right hand end thereof, so that as the conveyor 29 passes over the tank 38 from left to right in Figures 6 and 7, the buckets gradually drop away from around the match blanks 7 so that by the time the latter reach the right hand end of the tank 38 they are entirely free from said buckets, the latter being then dropped again into said tank for a fresh supply of paraffine. To insure the retention of the book leaves on the pins 35 of the swinging members 32 of the conveyor 29, an endless belt or chain 41 may be mounted above said conveyor 29 and be provided with projecting arms 42 to bear against said book leaves adjacent the points where they are engaged by said pins 35, as best shown in Figure 6. This belt or chain 41 carrying the bearing arms 42 preferably extends over the paraffine tank 38 and also over the ignition material tank 43 illustrated in Figures 8 and 9, although said belt is omitted in the latter figure for the sake of clearness.

The tank 43 for the ignition material is preferably provided with a hot water jacket 44 whereby said ignition material may always be kept in a sufficient fluid state to be handled for coating the tips of the match blanks 7 of the book leaves. An endless conveyor 45 carrying pivoted buckets 46 dips into the tank 43 and raises sufficient quantities of the ignition material in each bucket to coat the tips of the match blanks of each book leaf. At the left hand end of the tank 43, the conveyor 45 passes around a sprocket wheel 47 which serves to raise the bucket 46 out of the tank and to a level slightly below

the tips of the match blanks as they travel over the tank on the conveyor 29. As the buckets 46 reach the top of the sprocket wheels 47 they pass below a fixed transverse strip 48 which levels off the ignition material in the bucket, it being understood that said ignition material is of a rather thick plastic consistency which is apt to cause it to become heaped up in the center of the buckets which might result in a greater quantity than necessary being applied to the tips of the match-blanks. As the buckets advance from the left hand sprocket wheel 47 the conveyor 45 rises by reason of its passing over rollers 49 mounted on a slightly high level, in order to bring the buckets 46 up to a position where the tips of the match blanks 7 will dip therein, see Figure 8. Said tips of the match blanks remain in the buckets until both reach the right hand end of the tank 43 when said buckets drop again into said tank, and said match blanks are carried by the conveyor 29 beyond the tank to any suitable point of discharge.

Space is preferably provided between the paraffine tank and the ignition tank for the purpose of cooling the coating of paraffine on the match blanks before the tips thereof are dipped in the ignition material. This cooling may be accomplished by forcing a current of cold air on the match blanks for a time determined by the distance traveled between said tanks.

I claim:

1. In a paper match making machine, the combination with an endless conveyor, of transverse swinging members mounted at intervals on said conveyor and having projecting pins thereon to engage the binding perforations in the stubs of match book leaves for supporting the latter on said conveyor with their match blanks in depending position, a paraffine tank arranged below said conveyor, a train of buckets adapted to dip into said tank and apply a sufficient quantity of paraffine therefrom to coat the depending match blanks of each match book leaf as it passes over the tank, said bucket train being arranged on an incline for gradually removing them away from the match blanks as the latter advance toward the far end of the tank.

2. In a paper match making machine, the combination with an endless conveyor, of transverse swinging members mounted at intervals on said conveyor and having projecting pins thereon to engage the binding perforations in the stubs of match book leaves for supporting the latter on said conveyor with their match blanks in depending position, a paraffine tank arranged below said conveyor, a train of buckets adapted to dip into said tank and apply a sufficient quantity of paraffine therefrom to coat the depending match blanks of each match book leaf as it

- passes over the tank, said bucket train being arranged on an incline for gradually removing them away from the match blanks as the latter advance toward the far end of the tank; and an endless belt arranged above the conveyor for the match book leaves, said belt having projecting pins adapted to engage the stubs of said leaves and hold them in engagement with the pins on the swinging members of said conveyor during the paraffine coating operation.
3. In a paper match making machine, the combination with an endless conveyor, of transverse swinging members mounted at intervals on said conveyor, means on said members to engage in the stubs of match book leaves for supporting the latter on said conveyor with their match blanks in depending position, a tank for ignition material over which the conveyor passes, and a train of individual buckets one for each book for raising a sufficient quantity of ignition material from said tank and applying the same to the tips of said match blanks during their passage over the tank.
4. In a paper match making machine, the combination with an endless conveyor, of transverse swinging members mounted at intervals on said conveyor and having projecting pins thereon to engage the binding perforations in the stubs of match book leaves for supporting the latter on said conveyor with their match blanks in depending position, a tank for ignition material having a hot water jacket around the same for the purpose specified over which the conveyor passes, and a train of buckets for raising a sufficient quantity of ignition material from said tank and applying the same to the tips of said match blanks during their passage over the tank, and means for levelling off each bucket before the dipping operation for the purpose specified.
5. In a paper match making machine, the combination with an endless conveyor, of transverse swinging members mounted at intervals on said conveyor, and having projecting pins thereon to engage the binding perforations in the stubs of match book leaves for supporting the latter on said conveyor with their match blanks in depending position, a tank for ignition material having a hot water jacket around the same for the purpose specified over which the conveyor passes, a train of buckets for raising a sufficient quantity of ignition material from said tank and applying the same to the tips of said match blanks during their passage over the tank, a belt arranged above the conveyor for the match book leaves, and projecting pins on said belt to engage the stubs of said leaves for holding them in engagement with the pins on the swinging members of said conveyor during their passage over the tank.
6. In a paper match making machine, the combination with an endless conveyor, of transverse swinging members mounted at intervals on said conveyor and having projecting pins thereon to engage the binding perforations in the stubs of match book leaves for supporting the latter on said conveyor with their match blanks in depending position, a paraffine tank arranged below said conveyor, a train of buckets adapted to dip into said tank and apply a sufficient quantity of paraffine therefrom to coat the depending match blanks of each match book leaf as it passes over the tank, a tank for holding ignition material and having a hot water jacket arranged behind said paraffine tank and over which the conveyor for the match book leaves passes, a train of buckets for raising sufficient quantities of said ignition material from said tank to coat the tips of the match blanks of said leaves as the latter pass over the tank, a belt arranged above both the paraffine and ignition material tanks, and projecting pins on said belt adapted to engage the stubs of said match book leaves and retain them in engagement with the pins on the swinging members of the conveyor for said leaves during the passage of the latter over both tanks.
7. In a paper match making machine, the combination with an endless conveyor, of means on said conveyor for supporting match book leaves by their stubs and with their match blanks in depending position, said conveyor extending over said tank, a train of buckets separate from each other and mounted on an endless conveyor having its lower bight arranged in the tank and its upper bight arranged above said tank, each of said buckets being adapted to register with one of the match book leaves as the latter pass over the tank for coating the tips of the match blanks with said ignition material, means for levelling off each bucket prior to the dipping of the tips of the match blanks of the corresponding leaf into the same, and an idler roller for the bucket conveyor arranged in advance of the levelling device for causing the buckets to rise into position to have the tips of the match blanks dipped therein.
8. In a match making machine, a conveyor for match books, means on said conveyor for supporting a match book in depending position, a traveling bucket beneath said conveyor to receive the lower end of said book, a traveler overlying said conveyor, and a finger on said traveler for engaging said book and holding the same on said conveyor.
9. In a machine for making match-book leaves, the combination, with a continuously moving conveyor, of a train of leaf holders carried thereby, means for forming match-book leaves from a continuously moving strip of material and transferring the leaves

to the said holders without interrupting the continuity of movement of the said conveyor.

10. In a machine for making match-book leaves, the combination with a continuously moving conveyor, of means for forming match-book leaves and transferring them to the said conveyor, the whole being so organized that the said leaves during the transferring operation move substantially in the same direction and at the same speed as that of the said conveyor, whereby the leaves are received on the said conveyor without interrupting the continuity of its movement.
15. 11. In a machine for making match-book leaves, the combination with a continuously moving conveyor bearing a series of match-book leaf holders, of means for forming the said leaves and transferring them successively to respective leaf holders, the whole being so organized that the said leaves during the transferring operation move substantially in the same direction and at the same speed as that of the said holders, whereby the leaves 25 are received on the said holders without interrupting the continuity of the movement of the conveyor.

12. In a machine for making match-book leaves, the combination with a continuously moving conveyor, of means for operating upon a continuously moving strip of leaf material to form match-book leaves and for transferring the said leaves to the said conveyor, the whole being so organized that the said leaves during the transferring operation move substantially in the same direction and at the same speed as that of the said conveyor, whereby the leaves are received on the said conveyor without interrupting its continuity of movement.

13. In a machine for making match-book leaves, the combination with a continuously moving conveyor, of means presenting cutting edges adapted to cut a continuously advancing strip of leaf material to form match leaves each having a stub portion and a plurality of match blanks projecting therefrom, of a pair of rotating elements disposed on opposite sides of and with their axes arranged transversely of said leaves and each having a longitudinal series of pins projecting substantially radially therefrom to engage alternate match blanks of said leaves as the latter pass between said elements for spreading the free ends of the said match blanks alternately in opposite directions, the said pins also functioning to continue the advance of the leaves toward and in the direction of movement of the said conveyor after the said leaves have been completely severed from the advancing strip of card material.

14. In a machine for making match-book leaves, the combination, with a continuously moving conveyor, of a pair of co-operating

continuously rotating cylinders adapted to draw in a strip of leaf material and presenting a longitudinal series of annular cutting edges co-operating together during a part of a revolution to cut said strip longitudinally at intervals to form a longitudinal series of transverse rows of longitudinally extending match blanks, a continuously rotating cutter head having its axis and a cutting edge arranged transversely to the said strip so as to cut the continuously moving strip transversely at intervals in line with one end of each of the groups of match blanks for forming match book leaves, and continuously moving means for spreading alternate match blanks apart so as to separate their free ends and for simultaneously advancing the completely severed leaves from the said cutter-head and presenting them to the said conveyor in predetermined positions thereon.

15. In a machine for making match-book leaves, the combination, with a conveyor having pins thereon for holding match-book leaves and perforating them to provide openings for the said pins and subsequently transferring them to the said conveyor in predetermined positions thereon so that the said openings are engaged by the said pins.

16. In a machine for making match-book leaves, the combination with a continuously moving conveyor having pins thereon for holding match-book leaves, of means for forming match-book leaves from a continuously moving strip of leaf material and perforating them to provide openings for the said pins and subsequently transferring the said leaves to the said conveyor so that the said pins enter the said openings in the said leaves.

17. In a machine for making match-book leaves, the combination, with a conveyor having pins thereon for holding match-book leaves, of means for forming match-book leaves and perforating them to provide openings for the said pins, and means for spreading apart the free ends of the match blanks of said leaves and transferring the said leaves to the said conveyor in predetermined positions thereon so that the said pins are engaged by the said openings.

18. In a machine for making match-book leaves, the combination with a conveyor having pins thereon for holding match-book leaves, of means for forming match-book leaves and perforating them to provide openings for the said pins and for placing the said leaves on the said conveyor so that the said openings register with the said pins, and means for pressing the said leaves down upon the pins with which their openings register.

19. In a match making machine, the combination of a paraffin holder and a conveyor adapted to carry match blanks in depending

80

position and dip the same into the said holder, the organization being such that the blanks, immediately after being dipped in the said holder, are withdrawn gradually and uniformly therefrom as the conveyor advances.

20. In a match making machine, the combination of a paraffin tank, a plurality of buckets adapted individually to travel in succession in an endless path through said tank and rise therefrom and then pass down a gradual incline, and a conveyor adapted

to advance horizontally with and over the buckets on the said incline and to carry match blanks in depending position and in registration with the said buckets, whereby the lower ends of the blanks are dipped in the buckets at the head of the incline and are gradually and uniformly withdrawn therefrom as the conveyor and buckets advance. 20

In testimony whereof I have signed my name to this specification.

JULIUS J. FERRETTI.
